DESIGN FOR A PENCIL TIP

Michael Caffrey, Jersey City, N. J., assignor to American Lead Pencil Company, Hoboken,
N. J., a corporation of New York

Application March 25, 1936, Serial No. 61,776

Term of patent 3½ years

To all whom it may concern:

Be it known that I, Michael Caffrey, a citizen of the United States, residing at 500 Baldwin Avenue, Jersey City, in the county of Hudson and State of New Jersey, have invented a new,
original, and ornamental Design for a Pencil Tip, of which the following is a specification, reference being had to the accompanying drawing, forming part thereof.

plan view of a pencil tip, showing my new design.

I claim:

The ornamental design for a Pencil Tip, as shown.

MICHAEL CAFFREY.
